UNITED STATES PATENT OFFICE.

GUSTAVE LIDSEEN, OF CHICAGO, ILLINOIS, ASSIGNOR TO CONCRETE TILE MACHINERY COMPANY, OF CICERO, ILLINOIS, A CORPORATION OF ILLINOIS.

CONCRETE TILE MACHINE.

Application filed June 2, 1923. Serial No. 642,943.

To all whom it may concern:

Be it known that I, GUSTAVE LIDSEEN, a citizen of the United States, residing at Chicago, in the county of Cook and State of Illinois, have invented certain new and useful Improvements in Concrete Tile Machines, of which the following is a specification.

This invention relates to improvements in concrete tile machines and has for its object to provide a machine of that character in which new and improved means is provided for tamping and compacting, as well as forming the concrete tile from the aggregate.

Another object resides in the action and regulation of motion of the tamping member.

These and other objects will be more fully set forth and described in the following specification and shown in the accompanying drawings, in which—

Figure 1 is a plan view of my improved tamping device in assembled relation in a concrete tile machine;

Fig. 2 is a side elevation of the same, a portion of the mounting being broken away for clearness;

Fig. 3 is a vertical longitudinal section along the line 3—3 of Fig. 1;

Fig. 4 is a plan view of the tamper alone; and

Fig. 5 is a front elevation of the same.

Like numerals refer to like elements throughout the drawings. 10 and 11 indicate side frame members of a concrete tile machine. Only so much of the general mechanism is shown as to enable those skilled in the art to understand the process and function of the tamp-member. 12 indicates generally a charging hopper open at the bottom and supplied with aggregate or concrete by chute 13, located thereabove. Endless chains 14 are provided and actuated, these chains being provided with cross strips 15 between which extend, and upon which are supported the pallets 16 of desired contour. Partitions or separating plates 17 space the pallets and divide the tile during the formation thereof. Pallets are conveyed through charging hopper 12 in the direction indicated by the arrows in Fig. 3, during which travel they are charged or loaded with ag-

gregate, the height of this load being regulated by the position of the adjustable slide or gate 18, at the rear of the hopper 12, this being the exit point of the pallets. Located rearwardly of the hopper 12 in the direction of travel of the pallets and adjacent the exit of such pallets from the hopper, is the tamping member, generally indicated by numeral 20, of a contour conforming to the tile desired. In the embodiment shown, this tamper comprises a face plate 20^a, preferably stamped of steel and secured to the cast iron block 20^b by screws 20^c which are mounted to lie flush with the facing surface of the face plate 20^a, as shown in Fig. 5. The block 20^b is centrally bored or apertured as indicated by numeral 20^d, and shown in dotted lines in Fig. 4, for example, the portions 20^e at the ends of such bore being of relatively lesser diameter and preferably machined or fitted to form a true smooth surface for the coacting shaft described below. By coring out the intervening or enlarged portion of the bore 20^d, I reduce the frictional contact surface between the shaft, later described, and the block 20^b. Secured to the upper face of face plate 20, adjacent the rear end thereof, is the small channel member 20^f having its web 20^g secured by spot welding or the like, to such face plate. Between the walls 20^h of the channel 20^f extends the pin or bolt 20ⁱ upon which is rotatably carried the roller 20^k. At each side of the face plate 20^a adjacent the rear end thereof is a small angle 20^m having a flange likewise secured by spot welding, or the like, to the face plate, and an upwardly extending flange 20ⁿ provided with an aperture 20° therethrough for a purpose to be hereinafter described. At the rear end of the hopper 12 are the supporting brackets 12^a secured to the side frames 10 and 11 as shown in Figs. 1 and 2, for example, by removable bolts 12^b. Bolted to these brackets 12^a are the bearing blocks 25 secured in position by the bolts 26. These brackets are provided with alining bearing apertures 25^a, in which is journaled the shaft 27, one end of which is extended to carry the sprocket 28, actuated by chain 29 in the direction indicated by the arrow in Fig. 2. Shaft 27 is provided with an eccentric portion 27^a being rotatably mounted

in the reduced portions 20^a of bore 20^d. Located rearwardly of the shaft 27 and projecting upwardly from the side frames 10 and 11 are the pedestals 30, secured by 5 bolts 31, or the like, to said side frames. These pedestals are provided with notched or angularly formed seats 30^a at the top thereof, in which is seated the transverse polygonal bar 35. This bar is provided 10 with flattened seats 35^a at its exteremities at the upper side thereof. The pedestals 30 are provided with outwardly projecting bosses 30^b apertured to accommodate the pins 36, each of which provide a pintle for a locking bail 37 having the locking set screw 38 extending therethrough. These 15 bails 37 may be swung to overlie the flattened ends of the bar 35 and the locking screws 38 secured downwardly to seat upon the flattened seats 35^a, locking the bar 35 securely in seated position. To unlock and 20 permit removal of the bar, this operation is reversed. Suitable holes are provided in the lower side of the bar 35 overlying 25 flanges 20^a of the subjacent tamper, and one end of each of the springs 40, see Fig. 3, is attached in one of these holes, the other end being attached to one of the upstanding flanges 20^a, these springs being under 30 tension and normally functioning to draw the rear end of the face plate 20^a toward the bar 35. When in assembled relation, an inclined cam plate 41 contacts with the roller 20^k of the tamper, this contact being 35 maintained by the springs 40, as will be obvious. At its upper side the cam plate 41 is provided with the segmental recess 41^a, into which extends a lug 42^a of transverse plate 42, a pin 41^b extending through 40 the lug 42^a and serving as a pivot for the cam plate 41 during adjustment of the inclination thereof. This transverse plate 42 is attached by cap screws or the like to a 45 loop 43, which embraces the transverse bar 35, being constructed to slidily engage opposed faces thereof, to permit relative movement of the bar and loop parallel to said faces. An adjusting screw 44 is provided, having a reduced portion 44^a extending 50 through the bar 35 and secured to the bar by means of a pinned nut 45 at the outer side thereof. The nonreduced portion 44^b of the adjusting screw 44 is threaded for engagement with a coacting threaded aperture in the loop 43, coiled pressed spring 46 extending between the loop 43 and the head 44^c of the adjusting screw 44, this spring functioning in well known manner to permit intentional rotation of the adjusting screw but to prevent accidental rotation. 55 At each side of the transverse plate 42 and extending therethrough in threaded engagement therewith is an adjusting screw 47 having an engageable head 47^a and its 60 opposite end in contact with the surface of

the cam plate 41. Coiled pressed springs 48 extend between plate 42 and the heads 47^a of the adjusting screws 47.

By the construction described above the screws 47 may be adjusted to change 70 the inclination of the cam plate 41 at the pivot pin 41^b, as will be obvious. Likewise adjusting screw 44 may be actuated to slide the loop 43 and simultaneously the cam plate 41, relative to the bar 35. The roller 20^k is held in contact with the face of cam plate 41 by the springs 40.

The front end of the face plate 20^a is upturned and grooved, the rear end to a lesser degree being upturned and grooved as shown in Fig. 3, for example. In the operation of this device, as the pallets are charged to the proper height with the aggregate or concrete, during their passage through and out of the hopper 12, they are passed beneath the tamping member 20, which is actuating at a high speed, the front end being moved in a substantially elliptical orbit, due to the eccentric actuating shaft 27. During this actuation of the front portion of the tamper, the movement of the roller 20^k and consequently the rear end of the tamper, is regulated by the cam plate 41, the resultant action being to impart a sufficient compacting to the concrete to bring it to the desired density and configuration, and at the same time imparting a rubbing action to the surface, which serves to smooth and at least partially finish the same. It will be obvious also that this motion of the tamper is such that the front end will first engage and compact the subjacent concrete, while this is followed by similar action by the rear portion of the tamper. Also the front portion is first lifted or removed from the concrete so that instead of boldly lifting the entire face plate 20^a, there is a relatively gradual withdrawal which will destroy any partial vacuum between the face plate and the concrete. The height of the cam plate 41 may be adjusted to accommodate the necessary conditions although this adjustment having once been made, it is unlikely that subsequent adjustment is necessary during the life of any tamper, save possibly to accommodate slight wear. Similarly the angle of inclination of the cam plate 41 may be varied to properly restrain or regulate the motion at the rear end of the tamper and this too generally requiring little or no adjustment after once being properly set up.

When it is desired to inspect the tamper or underlying mechanism, the bar 35 may be released in the manner described and lifted bodily with the rear end of the tamper 20 through the engagement of springs 40, and the tamper rotated about the shaft 27, or the springs 40 may be disengaged from the tamper or bar to permit such inspection

after removal of the bar from locked position.

I have found in the manufacture of concrete tile by machinery that wear of the concrete face occurs due to the rubbing or friction between the concrete and the tamper, necessitating replacement of the tamper after a time. To meet this condition, I have constructed my tamping member with a removable and replaceable face plate 20^a as described above, which may be stamped of relatively thin sheet metal at a minimum of cost and permitting me to obtain an accurate face plate at less cost than where the same is constructed of cast iron. Likewise this ability to replace the face plate without disturbance of the carrying block, is a considerable advantage in cutting down the cost of replacement, as will be obvious.

20 I do not wish to be restricted to the embodiment of my invention described and shown except as defined in the appended claims.

What I claim is—

25 1. In mechanism of the class described, in combination with material carrying means, a tamping member, said member being eccentrically mounted adjacent one end and arranged for regulated movement vertically and horizontally adjacent the other end.

2. In mechanism of the class described, in combination with material carrying means, a tamping member, said member being eccentrically arranged adjacent one end and mounted for regulated movement vertically and horizontally adjacent the other end, and means to adjust the regulated movement.

3. In mechanism of the class described, in combination with material carrying means, a tamping member, eccentrically actuated means at one end of said member, and means to guide the other end of said tamper in a movement inclined to the vertical.

4. In mechanism of the class described, in combination with material carrying means, a tamper member, an eccentric actuating means coacting therewith at one end, and a cam member coacting with the other end to regulate its movement.

5. In mechanism of the class described, in combination with material carrying means, a tamper member, an eccentric actuating means coacting therewith at one end, and a cam member coacting with the other end to regulate its movement, said cam being adjustable to vary said movement.

6. In mechanism of the class described, in combination with material carrying means, a tamping member, means to move one end of said tamping member in an elliptical orbit, and means to convert the movement simultaneously imparted to the rear end to a combined vertical and horizontal movement.

65 7. In mechanism of the class described, in

combination, a tamping member, means to actuate one end thereof, a contact member carried adjacent the other end thereof, and a cam contacting with said last named member.

8. In mechanism of the class described, in combination, a tamping member, means to actuate one end thereof, a contact member carried adjacent the other end thereof, and a cam contacting with said last named member, said cam being adjustable as to position with respect to said contact member.

9. In mechanism of the class described, in combination, a tamping member, means to actuate one end thereof, a contact member carried adjacent the other end thereof, a cam contacting with said last named member, and means to normally maintain said contact member in contact with said cam.

10. In mechanism of the class described, in combination, a tamping member, means to actuate the same, an overlying supporting means, a cam plate carried thereby, said tamping member being provided with means contacting with said cam.

11. In mechanism of the class described, in combination, a tamping member, means to actuate the same, an overlying supporting means, a cam plate carried thereby, said tamping member being provided with means contacting with said cam, said cam plate being adjustable with respect to said tamping member.

12. In mechanism of the class described, in combination, a tamping member, means to actuate the same, an overlying supporting means, a cam plate carried thereby, said tamping member being provided with means contacting with said cam, said cam plate being adjustable with respect to said tamping member, both as to inclination and distance from said tamping member.

13. In mechanism of the class described, in combination, a tamping member, means to actuate the same, an overlying supporting means, a cam plate carried thereby, said tamping member being provided with means contacting with said cam, said plate being pivoted, and an adjusting member coacting therewith to adjust the position thereof of about said pivot point.

14. In mechanism of the class described, in combination, a tamping member, means to actuate the same, an overlying supporting means, a cam plate carried thereby, said tamping member being provided with means contacting with said cam, said supporting means being removable to permit swinging of said tamping member about said actuating means.

15. In mechanism of the class described, a tamping member, actuating means therefor operably attached adjacent one end of said tamping member, means to control the move-

ment of the other end of said tamping member, said last named means comprising a cam plate, carrying means for said plate, said plate being pivotally attached thereto, 5 and a transverse supporting member, said carrying means being adjustably attached thereto.

16. In mechanism of the class described, a tamping member, actuating means therefor operably attached adjacent one end of said tamping member, means to control the movement of the other end of said tamping member, said last named means comprising a cam plate, carrying means for said plate, said 10 plate being pivotally attached thereto, a transverse supporting member, said carrying means being adjustably attached thereto, and means to bodily adjust the position 15

of said cam plate with respect to said supporting means. 20

17. In mechanism of the class described, a tamping member, actuating means therefor operably attached adjacent one end of said tamping member, means to control the movement of the other end of said tamping member, said last named means comprising a cam plate, carrying means for said plate, said plate being pivotally attached thereto, a transverse supporting member, said carrying means being adjustably attached thereto, and means to adjust the position of said cam plate at its pivotal point. 25 30

In testimony whereof, I have subscribed my name.

GUSTAVE LIDSEEN.
